and the novel arrangement and assembly herein described to provide that a slider fastener and cloth could be used in combination with a garment and that the slider could be concealed at all times.

It is a general object of the present invention to provide a

UNITED STATES PATENT OFFICE

2,636,177

ZIPPER SHIRT

Morris L. Kaplan, Hazleton, Pa., assignor to The Shirtercraft Co., Inc., Hazleton, Pa., a corporation of New York

Application August 16, 1949, Serial No. 110,591

3 Claims. (Cl. 2—128)

1

The present invention relates to shirts, particularly dress shirts.

The object of the invention is to provide a construction in which the front edges of the shirt are united by a conventional slider construction, but in which the presence of the slider is effectively concealed at all times.

An additional object of the invention is to provide a construction wherein the likelihood of the free edges at the openings of the shirt sections becoming entangled with the slider fastener, when it is manipulated, is reduced to a minimum.

Referring to the drawings:

Figure 1 is a rear elevation partly broken away;

Figure 2 is a section on the line 2—2 of Figure 1;

Figure 3 is a detail view;

Figure 4 is a rear elevation of a modification;

Figure 5 is a section on the line 5—5 of Figure 4; and

Figure 6 is a detail view.

Referring to the drawings, the numeral 10 indicates a front section of a shirt to which is connected by a line of stitching 11 at the opening edge a fabric facing member 12 in which is enclosed a layer of a thermoplastic material 13. The fabric 12 is folded about the thermoplastic material 13, and its inner free edge layer 14 is further stitched, as shown at 14'. The member 12 forms the facing at the opening edge of the shirt section 10. On the inner side of the member 12, there is positioned the slider structure or unit which is illustrated in detail in Figure 3. This comprises a layer of thermoplastic material 15 and the fabric stringer 16 carrying the slider members 17. The layers 15 and 16 are double stitched, as shown at 18 and 19, with the slider members projecting to one side of the layer 15. The unit shown in Figure 3 is stitched to the inner layer 14 of the member 12 by lines of stitching 20 and 21, and it will be noted that the slider structure is located remote from the free edge 22 of the facing 12. Referring to Figure 3, it will be noted that the line of stitching 18 forms a fold line for exactly locating the position of the slider structure, as shown in Figure 2 at 23. In this connection, the free edge of the shirt front section 10 is folded upon itself, and stitched to the layer 14 adjacent the slider structure, as shown at 24, to further aid in precisely locating the slider. In this manner, entanglement of the free edges at the opening of the shirt will be reduced to a minimum when the slider is manipulated.

2

The stringer is folded inwardly over the unit shown in Figure 3 on the line 18, and the complete assembly shown in Figure 2, are subjected to a heating and pressing operation which fuses the thermoplastic layer 15 and allows the sliders 17 to act as mold members and form embossments or recesses 25 in the stringer layer 16. Thus, the sliders 17 will always be registered with the recesses or molded pockets 25 and when the garment is washed and subsequently pressed, there will be no embossments appearing on the surface 26 of the front facing member 12. That is, this front edge facing member 12 will always be smooth and plane under the ironing operation, since sliders 17 will be registered in the recesses 25 and will not further emboss the facing member 12 when the garment is pressed.

The construction shown in Figures 4, 5 and 6 is similar to that shown in Figures 1, 2, and 3 except that in this construction, the thermoplastic layer 30 is stitched to a cloth backing 31 by a line of stitching 32. This unit is then interposed beneath the layer 14 of the edge facing member 12, as shown in Figure 5, whereupon, the stringer 16 and the free folded edge 33 of the section 10, the unit and the layer 14 are stitched together in any suitable manner, as shown at 34. Of course, the stringer 16 may be independently stitched to the unit 30—31 if desired and disposed exteriorly of the layer 14 as shown in Figure 2. Whether the unit 30—31 is independently stitched or assembled with the section 10 by the line of stitching 34, the embossments or recesses 25 can be molded in the layer 14, as above-described, upon a suitable heating and pressing operation. Where the unit 30—31 is independently stitched to the stringer, a second line of stitching will, of course, be required to unite the folded edge of section 10 with the stringer and the unit 30—31.

By reason of the present invention, it is possible to provide a shirt in which the opening is closed by a slide fastener or zipper, and wherein the same will be concealed at all times. Particularly, and as pointed out, repeated ironing of the shirt will not cause embossments to appear in the surface member 12, which is a decided improvement over previous constructions. This is due to the fact that the recesses 25 are molded either in the slider fabric layer 16 or in the layer 14 of the member 12, whereby the sliders register with these recesses and being embedded therein, there is no opportunity for the slider 17 to be impressed in the facing 26 of the member 12.

Moreover, it is to be noted that the slider structure is located centrally with respect to the

inner side of the facing 12, and is positively located by reason of the fold line 18 of Figures 2 and 3 upon which the slider fabric is folded upon itself, and in every case, by the folded edge portion 33 of the shirt section 10, as shown in Figures 2 and 5, which is secured by stitching to the layer 14.

I claim:

1. A shirt facing comprising a facing layer, a shirt section secured thereto on the inner side of the facing, said facing layer having a free edge portion on the inner side of the facing, a layer of thermoplastic material disposed beneath said free edge portion, and a stringer secured on the outer side of the free edge portion and carrying sliders overlying said free edge portion and said thermoplastic layer therebeneath, said free edge portion having a multiplicity of pockets formed therein by molding the sliders into said free edge portion when the facing is subjected to heat and pressure and said thermoplastic layer is fused. 20

2. A shirt facing comprising a facing layer, a shirt section secured thereto on the inner side of the facing, said facing layer having a free edge portion on the inner side of the facing, a stringer carrying sliders secured to said free edge portion of the facing, a layer of thermoplastic material disposed between said stringer and said free edge portion, said sliders overlying said

stringer and said thermoplastic layer, the said stringer having a multiplicity of pockets formed therein by molding the sliders into the stringer when the facing is subjected to heat and pressure and said thermoplastic layer is fused. 5

3. A shirt facing comprising a facing layer, a shirt section secured thereto on the inner side of the facing layer, said facing layer having a free edge portion including a fabric layer on the inner side of the facing layer, a stringer carrying sliders connected to said free edge portion on the inner side of the facing layer, and a thermoplastic layer connected to said free edge portion of the facing, said sliders overlying said last-mentioned thermoplastic layer, and the fabric layer directly beneath said sliders being provided with a multiplicity of pockets formed by moulding the sliders therein. 15

MORRIS L. KAPLAN.
